UNITED STATES PATENT OFFICE.

DAVID E. CHISM, OF STAFFORD SPRINGS, CONNECTICUT.

CASH-CARRIER APPARATUS.

No. 851,844.

Specification of Letters Patent.

Patented April 23, 1907.

Application filed May 28, 1906. Serial No. 319,111.

To all whom it may concern:

Be it known that I, DAVID E. CHISM, a citizen of the United States of America, and a resident of Stafford Springs, in the county of Tolland and State of Connecticut, have invented certain new and useful Improvements in Cash-Carrier Apparatuses, of which the following is a full, clear, and exact description.

- 10 This invention relates to improvements in cash carrier apparatuses of a kind in which the cash box is supported and guided along suitable trackways therefor, and propelled by an endless cable, and is generally for the improvement of a cash carrier having the characteristics shown and described in Letters Patent of the United States granted to Chamberlain, Chism and Cooper, Nov. 5, 1901, No. 685,740, to Chamberlain and Chism granted August 8, 1905, No. 796,808, and to me, granted May 22, 1906, No. 820,955,—the type of cash box employed being shown in Letters Patent granted to me March 15, 1904.
- 15 The objects of the invention are: to improve the construction of the supporting brackets or fixtures for the cable guiding wheels at the home station whereby the mounting of such fixtures for any given number of pairs of sending and receiving trackways and cable guiding wheels corresponding thereto may be set up and maintained in an easy, practical and accurate manner, and whereby such fixtures at the home station 30 will have a sightly appearance; and in connection with such home station fixtures, the improved cable guards are provided adjacent the cable guiding wheels or sheaves; and the terminals of the receiving trackways are 35 made so that a cash box coming thereto from a clerk station will be retained thereat without liability of accidental displacement, although the receiving track terminals are constructed in such a manner as to permit, easily, the purposed taking out of the cash box; to provide appliances and means of connection whereby tubular portions of the track may be combined with track continuations which are of double rail or parallel rod form; to provide an improved formation of tubular trackway having a central longitudinal slot along its under side whereby increased width of bearing for the neck of the cash box is provided at the opposite sides of the slot way so that the cash box will run along without liability of transverse swaying motion so that

the engagement between the cash box head and the cable may not be disturbed, and so that the cash box in coming to a switch therefor will be, with greater certainty, in its proper position to receive the engagement, by the switching tongue, with the switch tongue engaging portion of the box; to improve the construction of the comparatively short branch track section included at a track station with respect to the provisions whereby the cash box coming thereto is retained against displacement, and yet is capable of being positively withdrawn by the clerk, so that the clerk stations may be made up without regard to "rights and lefts" whereby they may be installed in any situation still leaving it possible, and fully as convenient, for the clerk to withdraw the cash box from one side as from the other; to improve the corner constructions,—that is the portions of the cash carrier apparatus provided for the support of a comparatively large cable guiding wheel, such supporting constructions having the form of sectionally made castings, which when assembled and united form supports for the journal axle of the wheel and tubular trackway sections at right angles and adjacent the wheel with a suitably positioned slotway in such tubular track sections for the accommodation and free running of the neck of the cash box; and generally to improve and simplify the constructions and the making of them to conform to mechanical and workmanlike principles. And to these ends the invention consists in constructions and formations of parts, and combinations and arrangements of parts all substantially as hereinafter fully described and set forth in the claims.

The present improvements are illustrated in the accompanying drawings, in which,—

Figure 1 is a side elevation of the portion of the cash carrier apparatus including the home station at which the cash containing boxes are received, and from which they are sent, a corner construction in one double line of track, and a clerk station connected by a branch with one of the sending trackways. Fig. 2 is a side elevation on a larger scale showing the supporting structure in stacked form for two pairs of trackways and for the cable guiding sheaves or wheels near but forwardly of the rear ends of the trackways. Fig. 3 is a rear end view of one of the sending trackways showing an indicating number therefor. Fig. 4 is a plan view of the under

side of the rear end portion of one of the receiving trackways. Fig. 5 is a side elevation of the parts shown in Fig. 2, and as seen at right angles thereto, and as viewed from the forward thereof, the trackways being shown in cross section and one pair thereof being of a modified construction. Fig. 6 is a plan view of Fig. 2. Fig. 7 is a perspective view showing a portion of a pair of rod formed trackways, and the device for uniting two rods of one of the tracks. Fig. 8 is a side elevation of intermediate portions of sending and return tracks together with a clerk station connected with and branched from the sending trackway. Fig. 9 is a plan view of the under side of the portions of the several trackways shown in Fig. 8. Fig. 10 is a cross sectional view as taken on the line 10—10, Fig. 8, and including a bracket in elevation and understood as having its position remote from the branch. Fig. 11 is a cross sectional view, on a larger scale, as taken on line 11—11, Fig. 8. Fig. 12 is a perspective view showing the sectionally made and separable parts of a corner construction in separated relations. Fig. 13 is an elevation as seen at the right hand end of Fig. 12, the parts being in their assembled relations. Figs. 14 and 15 are somewhat similar end views to be hereinafter referred to.

Similar characters of reference indicate corresponding parts in all of the views.

In the drawings,—A represents a cashier's or "home station" comprising a suitable desk or table *a* secured on which is a base plate *b* having formed as one therewith, or attached thereto, a post or round standard *d* which is entirely firm in its anchorage to the table.

B and C, and B² and C² are two pairs of trackway terminals, those B and B² being for the sending trackways and the terminals C and C² are for the return or receiving trackways, all thereof terminating at the home station A, the ends of the sending trackways being in the same vertical line, while the extremities of the receiving trackways are extended beyond the ends of the sending trackways.

D and D² each represent a double bracket frame for the support of the two pairs of trackway terminals, for the sheaves 10, 11, 12, and 13 which have their locations slightly forward of the rear ends of the tracks and around which the endless carrier cables are guided, and also for the support of the adjustable cable guards 20, 21, 22 and 23. Each bracket frame D or D² comprises three axially aligned hubs or collars 15, 16 and 17, for sliding fit about the post *d*, more or less of such apertured hubs being penetrated by set screws 18 whereby the frames are bound to the post and held so that they may neither be displaced from their properly adjusted positions vertically or rotationally.

The yokes *e* and *f* of each bracket frame are set at opposite sides of the axis of the boss, and one above the other, as most clearly represented in Figs. 5 and 6,—the bottom member of the upper yoke being at 70 or about the level of the top member of the lower yoke, the intermediate apertured hub 16 forming connection or strengthening brace between the two yokes.

The sheaves or guide wheels 10, 11, 12, and 13, are mounted for rotation on axes oblique to the trackway lines, are arranged with peripheral portions thereof in proximity or coincident with the lines of run of the cables within or along the trackways, and are slotted to guide the cord from and into lines transversely offset from the trackway lines whereby the trackway terminals may have their locations rearwardly beyond the positions of the said guide wheels.

The positioning and oblique arrangement of the guide wheels has been illustrated and described in my former patent of May 22, 1906, but in that patent the stack of track and sheave supports was built up by each 90 relatively upper support having connection with, and sustained by, the next one therebelow; but in the present case these supports are fitted about and have set screw connections adjustable with a common, preferably 95 cylindrical, post, and while generally one set of bracket frames will be superimposed on another, the frames may be mounted as occasion may sometimes require, or render more advantageous, with the bottom of one 100 considerably above the top of another.

The upper portions 19 of the several yokes *e* and *f* are horizontally slotted for the connection thereof of the plates 25, of the cable guards 20, 21, etc., the inclination of the 105 lower wheel 10 or 12 of the several sets of guide wheels being such that there is no tendency for the cable to run off only at one edge of the wheel, single guard only being provided for such wheels, while the other 110 wheels 11 and 13 being mounted for rotation in vertical planes (oblique, however, to a vertical plane longitudinally and median of the several trackways), and there being liability that the cable might run off at either edge of 115 the wheels, the cable guards 21 and 23 are made with double guard members, as more clearly shown in Figs. 2 and 5, and the member or members of each of the guards is integrally formed with its attachment plate 25 120 which has screw holes 26, 26, for receiving, with screw thread engagements therein, the confining screws, the shanks of which are extended through the slots 27 and the top members 19 of the yokes, while the heads of 125 said screws are firmly set against the sides of the yoke members.

By loosening the set screws and slightly sliding the guards, the latter may have their most suitable positions in proximity to, but 130

free from, the edges of the cable guiding wheels.

The lower member 30 of each yoke is made with a break therein for the accommodation 5 of the tubular trackway terminal, the attachment members 32, 32, being provided through which confining screws 33 may be passed with engagements into the trackway terminals.

15 F represents the cable driving drum at the home station, the same being supported for rotation in suitable bearings under the desk or table a; and G represents one of the endless cables the same passing from around the drum upwardly around the guide wheel 11, thence through an opening in the top of the track terminal B and outwardly proceeding to the other end of the cash carrier system having its return course back along the 20 ceiling trackway and passing through an opening in the upper part of the terminal C around the guide wheel 10 and back around the driving drum F; and the cable G² similarly passes from the drum upwardly through 25 the table around the guide wheel 13 to within the terminal B² of the upper sending trackway, returning through and emerging from the terminal C², thence around the guide wheel 12 and back to the driving drum F.

30 The cash box H has the longitudinally extending thin neck 38 between its body and its approximately cylindrical head 39 which has the longitudinal sinuous channel 83 therein for engagement with the cable in the manner 35 heretofore commonly practiced, and as set forth in the aforementioned patents.

The terminals of the portions of the trackways C and C² located at the home station, supported as described, and extending rearwardly beyond the rear ends of the sending trackway terminals are made as represented in Figs. 2 and 4, that is the terminal is somewhat enlarged at its rear end, has a rear end wall 40, a transverse aperture 42 therethrough, 45 an opening 43 at its bottom, the rear portion 44 of which is of an obtuse V-shape while the under longitudinal slotway 45 of the tubular track terminal C or C² leads to, and ends at, the aperture 43, and at its junction therewith 50 it is rearwardly divergent, as shown at 46.

41 represents a buffer of rubber or other suitable material at the rear end wall 40.

The cash box returning to the home station as propelled thereto by the cable, will, after 5 leaving the cable at the point adjacent the guide wheel, proceed by momentum through the rearwardly extended part of the track terminal, and will be arrested by contact against the buffer 47 and will remain in the 60 position as represented in the lower right hand portion of Sheet 2 of the drawings in readiness to be removed.

The removal of the cash box will be by manually imparting thereto a sidewise swinging movement and then a rearwardly sliding

movement while the box may be withdrawn rearwardly and obliquely relatively to the length of the track.

The trackway terminals B, B², and C, C², are preferably made in the form of tubular 70 castings, and the trackways forwardly in continuation thereof may be of the well known tubular under-slotted form, as represented at B³, C³, in Fig. 1 and the lower portions of Figs. 2 and 5, or the trackways may be of the 75 double rod or rail form, as represented at B⁴ and C⁴ at the upper portions of Figs. 2 and 5, and in Figs. 6 and 7.

In some cases the tubular form of trackway is to be preferred, but in others where 80 lessened cost is a consideration, the rod form may be used.

Where the tubular under-slotted trackways are employed the ends thereof in connection with the terminals, as B and C, are 85 telescoped into the forward end portions of the terminals, as shown, and held by friction, or additionally by having burrs or teats 47 which may be crowded or snapped into sockets 48 in the terminal sections, as shown in Fig. 2, and also substantially as shown, in a coupled intermediate portion of the return trackway shown in Fig. 8 in which latter view the teats or lurs 47 produced by indenting or outwardly forcing the metal of the 90 tubing, have engagements in the small perforations or sockets 48^a in the sleeve coupling 50 which is employed for uniting two sections of the tubular track.

The track terminals may most advantageously be made in the form of castings to be sidewise adjoined and held together by the connecting screws 51, passed through 100 standing and matching ear pieces 52 and by the attachment pieces 32 and confining 105 screws 33 of the yokes of the bracket frames.

Where paired, parallel track rods are employed their extremities are overlapped along the under sides of the tubular terminal castings at opposite sides of the slotway, such 110 castings having formations adapted thereto and are retained by nearly circular clips 55 which embrace the terminal castings and are connected to the rods by pins or rivets 56.

At different places along the length of the 115 rod-formed trackway two pairs of tracks are united by tie brackets 57 made with parallel separated horizontal attachment lugs 58 which are pinned or riveted to the track rods, and the rods of a given double track are, furthermore, united at suitable intervals by nearly circular or arched ties 59, which are also, by suitable connections as pins, rivets or screws, attached to the rods.

J represents a branch of the sending trackway for a clerk station, the same having in its under side an opening 60 for the withdrawal of the cash box. A pair of frames 62, 62, are pivotally mounted on a pivot rod 63 of upstanding ear lugs 64 formed on or at- 120 125 130

tached to the upper portion of the branch trackway, a spiral spring 65 being coiled around the pivot while the opposite extremities thereof have yielding bearings on the op-

- 5 posite frames to keep them normally in their closed positions,—and that is, with the inner surfaces of their bar like members within the opposite edges of the opening 60 but still somewhat separated as shown in Fig. 9 and
10 by full lines in Fig. 11, to leave free way for the cash box neck, but to support the cash box head.

The cash box coming into the branch may, by being grasped by the hand and positioned
15 with the ends of its head 39 within the ends of the opening 60, be drawn downwardly and out from the branch trackway, the closing devices 62, 62, yielding as indicated by the dotted lines in Fig. 11; and with the clerk
20 station branch provided with a device of this character, it is immaterial at which side of the branch the person stands, and portions of cash carriers including clerk stations may be made up in large numbers without reference
25 to right or left hand positions in installation, and for as great convenience of use in right hand stations as in left hand stations.

An example of a corner construction is shown in perspective in Fig. 12, the constitutive parts thereof being shown in separated relations. This particular corner is well known as a lower vertical plumb corner, and the parts which support the comparatively large cable guiding wheel L have portions of
35 the trackways connected thereto generally at right angles to each other, as well known, and to some extent indicated in Fig. 1. This corner construction is shown as consisting of separated complementary sections comprising
40 opposite quadrant portions 70 and 70^a, and endwise continued partially tubular portions 72, 72^a, in which the curved sections are merged, such sections 72 and 72^a for each section being straight as to their lengths and
45 right angular to each other, and these have formed as one, or connected therewith, the axle supporting braces 73 and 73^a obliquely arranged relatively to the angularly disposed end portions of the said sections. The sections are preferably made as castings, and the oblique braces are integrally cast with the portions 70, 72, etc., and they are outwardly offset, as indicated at 74 to give ample space
50 between them for the cable guiding wheel,
55 the hub of which is considerably elongated, as shown. 75 represents the axle supported by, and affixed to the braces, and on which the cable guiding wheel loosely rotates. Said angularly disposed end portions 72, 72^a of the
60 separable castings, have edgewise located matching perforated ear lugs or members 76, 77, through which fastenings, as rivets or screws, are employed for rigidly uniting the sections of the corner construction. The

member 77, by means of which attachments 65 can be made, may be comprised in the aforementioned braces, as clearly indicated by the drawings.

In some cases where the corner constructions are for top plumb corners or horizontal 70 corners where the slotway 45^a or opening for the neck of the cash box is at the side of the wheel, and transverse to the plane of rotation of the wheel instead of coincident or parallel therewith, as possible for a lower vertical corner, the corner constructions may be made up of three sectional castings, 70, 70^a, and 70^b, as cross sectionally indicated in Fig. 15.

The trackway tubing having the median bottom slotway is, as shown in several of the 80 figures, made with opposite parallel continuous longitudinally depending lips 80 to give increased height of the opposite walls of the slotway whereby the flat neck of a cash box may be engaged along wider portions of 85 its opposite surfaces, and whereby consequently the box in its traveling movement will have lessened possibility of swaying from side to side; and the cash box by being constrained to run more evenly will be without 90 tendency to loosen its engagement with the propulsion cable, and, as more especially important, will on its approach to a switch be maintained in its proper position to impinge against the switch therefor, so that its course 95 may be diverted to the clerk station to which it is intended to go.

I claim:—

1. In a cash carrier apparatus the combination with a post, a plurality of bracket- 100 frames supported one above another by said post, track terminals, supported by said bracket frames, and cable-guiding-wheels supported by said frames, and located adjacent to intermediate portions of said track 105 terminals.

2. In a cash carrier apparatus the combination with a cylindrical post, a plurality of bracket-frames, each having an apertured hub, such hubs of the several bracket frames 110 embracing the post, one above another, and set screws engaged through said hubs and binding them to the post, track-terminals supported by said bracket frames, and cable-guiding-wheels supported by said frames, 115 and located adjacent to intermediate portions of said track terminals.

3. In a cash carrier apparatus the combination with a post, a plurality of bracket-frames each comprising integrally formed 120 upper and lower, and oppositely located yokes, and having at their inner edges the vertically axially aligned apertured hubs, and the binding screws therefor, said frames, by means of their said hubs embracing, and being secured, one above another on said post, track terminals, supported by said bracket frames, and cable-guiding-wheels 125

supported by said frames, and located adjacent to intermediate portions of said track terminals.

4. In a cash carrier apparatus the combination with a post, a plurality of bracket frames each for a pair of trackway terminals supported one above another by said post, track terminals, supported in pairs respectively by said bracket frames, and cable-guiding-wheels supported by said frames, and located adjacent to intermediate portions of said track terminals.

5. In a cash carrier apparatus the combination with a post, a plurality of bracket frames each for a pair of trackway terminals supported one above another by said post, and each comprising upper and lower yokes one edgewise offset from the other, the bottom member of one yoke being at the same level with the top of the other yoke, and having between them the apertured hub 16 and the upper and lower yokes being provided with the apertured hubs 17 and 15 which with the one 16 are vertically axially aligned, and set screws for binding said hubs to the post, track terminals, supported in pairs respectively by said bracket frames, and cable-guiding-wheels supported by said frames, and located adjacent to intermediate portions of said track terminals.

6. In a cash carrier apparatus a tubular terminal portion of a receiving or return trackway having an underneath longitudinal slotway, a rear end stop, a side opening, and a bottom recess merging in the side opening and with the forward end of which the slot connects.

7. In a cash carrier apparatus a tubular terminal portion of a receiving or return trackway having an underneath longitudinal slotway, a rear end stop, opposite side openings, and a recess merging in the side opening and with the forward end of which the slot connects.

8. In a cash carrier apparatus a tubular terminal portion of a trackway having an underneath longitudinal slotway, a rear end stop consisting of a yielding buffer and having a side opening and a widened bottom recess merging in the side opening and with the forward end of which the slotway connects.

9. In a cash carrier apparatus a tubular terminal portion of a trackway having an underneath longitudinal slotway, a rear end stop, a side opening, and a widened bottom recess merging in the side opening and, the boundaries of the slotway being divergent at the junction of such slotway with the said bottom recess.

10. In a cash carrier apparatus a tubular terminal portion of a trackway having an underneath longitudinal slotway, opposite side openings, and a widened bottom recess merging in the side opening and, the boundaries of the

slotway being divergent at the junction of such slotway with the said bottom recess, and said trackway having a bottom portion to the rear of said bottom recess which is of a forwardly directed V shape.

11. In a cash carrier apparatus, the combination with a tubular terminal portion of a trackway having an underneath longitudinal slotway, a rear end stop, a side opening, and a widened bottom recess merging in the side opening and with the forward end of which the slotway connects, of a cash box comprising a body, a horizontal longitudinally ranging substantially cylindrical head, and a flat longitudinally ranging neck connecting the body and head.

12. In a cash carrier apparatus, the combination with a tubular portion of a trackway having an underneath longitudinal slotway, a rear end stop including a buffer, and having opposite side openings, and a widened bottom recess, the boundaries of the slotway being divergent at the junction of such slotway with the said bottom recess, and said trackway terminal having a bottom portion to the rear of said bottom recess which is of a forwardly directed V shape, of a cash box comprising a body, a horizontal longitudinally ranging substantially cylindrical head, and a flat longitudinally ranging neck connecting the body and head.

13. In a cash carrier apparatus, the combination with a tubular metallic trackway having an underside continuous longitudinal slotway and having the metal at the opposite sides of the slotway down turned, imparting increased height of wall surface for the slot, of a propulsion cable running within the tubular trackway, and a cash box comprising an approximately cylindrical longitudinally grooved head,—for disposition in the trackway and to be engaged by the cable,—a body below the head, and a thin vertical longitudinally ranging neck connecting the body with the head and adapted for guidance between the widened walls of the slotway.

14. In a cash carrier apparatus, the combination with a clerk station branch trackway of underslotted, tubular, form, and having a widened aperture at its bottom intersected by the slot,—of oppositely located devices for contracting the width of said aperture, normally having their edges approached but separated from each other at opposite sides of the line of slotway, and adapted to yield oppositely and outwardly.

15. In a cash carrier apparatus, the combination with a clerk station branch trackway of underslotted, tubular, form, and having in an intermediate portion thereof a widened aperture at its bottom intersected by the slot,—of oppositely located frames pivotally mounted on the trackway and comprising members extending partially across,

and for contracting the said aperture, and a spring for yieldingly maintaining said frames in their approached relations.

16. In a cash carrier apparatus, the combination with a clerk station trackway of tubular, underslotted, form, and having in an intermediate portion thereof a widened aperture at its bottom intersected by said slot, and having at its upper portion at the location of said aperture upstanding ear lugs,— of oppositely located curved frames pivotally connected to said ear lugs and comprising lower bar-like members having their positions normally across and for contracting, the said aperture, and a spring for imparting a yielding closing pressure to said frames.

17. In a guide-wheel corner-construction

for a cash carrier apparatus, separable complemental sections comprising opposite quadrant portions, and endwise continued partially tubular portions into which the curved sections are merged, having their lengths angular to each other, and axle supporting braces obliquely arranged relatively to said angularly disposed end portions, and joined thereto, and means for detachably connecting the complemental sections.

Signed by me at Springfield, Mass., in presence of two subscribing witnesses.
